G. L. THOM.

TOY.

APPLICATION FILED FEB. 8, 1915.

1,182,055.

Patented May 9, 1916.

UNITED STATES PATENT OFFICE.

GEORGE L. THOM, OF BROOKLYN, NEW YORK.

TOY.

1,182,055.

Specification of Letters Patent.

Patented May 9, 1916.

Application filed February 8, 1915. Serial No. 6,843.

To all whom it may concern:

Be it known that I, GEORGE L. THOM, a citizen of the United States, residing at Brooklyn, in the county of Kings and State 5 of New York, have invented certain new and useful Improvements in Toys; and I do hereby declare the following to be a full, clear, and exact description of the invention, such as will enable others skilled in the art to 10 which it appertains to make and use the same.

This invention relates to toys, and more particularly to that type of jointed figures, in which the several parts thereof may be 15 assembled in several different relationships to present different attitudes.

An object of this invention is to provide a toy comprising several detachable parts which may be assembled to present the figure 20 in different attitudes.

A further object of this invention is the provision of an improved means for fastening the several parts together.

A further object of this invention is the 25 provision of jointed figures, which may be assembled in different positions, and which may be assembled with other figures of which the parts are similarly assembled.

Further objects will be apparent from the 30 following specification, appended claims, and drawings, in which,

Figure 1 is a perspective view of a figure made in accordance with this invention, Fig. 2 is a view of the several parts disassembled, 35 showing the parts in plan, Fig. 3 is a perspective view of the parts which when assembled form an animal, Fig. 4 is a plan view of an attachment to form a pedestal, and Fig. 5 is a similar view of a unit affording a support carried by one figure, to support another figure.

This invention provides for the formation of figures of a number of parts, which may be assembled in different relative positions, to present the figure in various positions, and, in carrying out the features, any figure may be presented, such as a person, animal, or flower. The same principle is present in any adaptation, and that is, to 45 have a number of sections, which have locking engagement with each other, and said locking engagement being had through one of several duplicate means in each of said sections.

50 Referring to the drawings, there is shown

a body portion 10, on which a head 11 is detachably mounted, and likewise, arms 12 and legs 13 are attached to said body. The head has a neck portion which is adapted to fit in one or another of the notches 14 formed in the body portion, and said neck portion is slotted as at 15 so that said head will be held in the desired position. The shoulders of the body are provided with a series of slots 16, which are adapted to receive one or another of the 65 slots 17 formed in the arms 12, and the body portion is further provided with the slots 18, adapted to receive the slots 19 formed in the leg sections. It is apparent that by the formation of the several parts shown, 70 the relative parts may be assembled in any one of the coacting slots to present the figure in any of a number of positions. Furthermore, by the formation of the slots as described, the several parts of the figure 75 may be made of light material such as cardboard, and the slots may be of such proportions as to cause the parts to have a snug fit when assembled, so that they will remain in fixed position.

The leg sections may have the feet 20 formed thereon, of the desired proportions to maintain the figure in upright position when the parts are put together, and when the figure is to be balanced on one leg, a 85 cross piece may be attached to the foot to provide sufficient foundation, and this piece is slid in the slot 21 of the leg sections, as shown at 22, having the slot 23 to engage the opposite sides of the foot above the 90 slot 21.

The same principle is carried out in presenting an animal, and as shown in Fig. 3, there is a body portion 25, adapted to receive a neck portion 26, and leg sections 27, 95 and 28. The body portion 25 has a plurality of slots 29 formed to receive the fore legs 27, and the neck portion 26 has a plurality of slots 30, of which any one may coincide with any one of the slots 29 to receive the section 27. To compensate for the double thickness of the body and neck portions, the section 27 has an enlarged slot 31 formed in the upper end thereof. The body section 25 is further provided with the slots 32 to receive the section 28, and the section 28 is slotted as at 33 to engage the opposite sides of the body portion when the two parts are assembled. The neck section may have the head made integrally therewith, and the 110

ears 34 may be detachable in providing them with a slotted portion 35 to engage in one or the other of the slots 36 formed in the head.

- 6 When it is desired to fasten several figures together, such as to mount the man upon the animal, the body portion 10 may have a slot 24 formed therein, which engages in the slot 37 formed in the body portion 25,
10 or if the figure is to stand upon the animal, the slot 38 may support a section 39, which has a slot 40 formed in the lower edge for engagement with the slot 38, or the slot 37 if desired, and the upper edge of this section has slots 41 formed therein to receive the slots 21 of the leg sections of the figure.

It is apparent that the slots formed in the complementary portions serve to hold the two parts in rigid relation with respect to each other, in having the slotted portion of one section straddle the body portion of the other member. Furthermore, it is clearly seen that the parts may be assembled to present any of a number of positions, with 25 the figures in any poise.

Various modifications may be made in view of the foregoing without departing from the spirit of this invention, and the drawing is submitted for illustrative purposes only.

Having thus described this invention, I claim:

- 30 1. A toy of the class described, comprising a plurality of relatively thin sections comprising a complete figure, or a combination of figures, each section having a definite relation to the other sections, and each section having a plurality of diverging slots formed

therein to engage in corresponding slots of the adjacent section. 40

2. A toy of the class described, comprising a plurality of flat sections which when assembled form a complete figure or combination of figures, each section having a definite relation with the other sections, each 45 section having a plurality of diverging slots adjacent that portion of each section to receive another section, each slot of each section being engageable in another slot of the adjacent section, and each section having engagement with the adjacent section by having the plane thereof perpendicular to the plane of the other section. 50

3. In a toy of the class described, a plurality of sections comprising a complete figure or combination of figures, each of said sections being of relatively flat material, each section having a series of definite associations with the adjacent section or sections, each section having a plurality of diverging 55 slots formed therein in proximity to the region of attachment of other sections, said sections being insertible in some of said slots formed in the other sections, the portions of material on each side of the slot engageable 60 with the other section reinforcing the assembling of the section, and said sections being attachable in any of a number of combinations. 65

In testimony whereof I affix my signature 70
in presence of two witnesses.

GEORGE L. THOM.

Witnesses:

HELEN LOWENSTEIN,
HUGO MOCK.
